UNITED STATES PATENT OFFICE.

LEVI H. GOODWIN, OF CINCINNATI, OHIO.

IRON WHEEL.

SPECIFICATION forming part of Letters Patent No. 293,006, dated February 5, 1884.

Application filed September 22, 1883. (No model.)

To all whom it may concern:

Be it known that I, LEVI H. GOODWIN, a citizen of the United States, residing at Cincinnati, county of Hamilton, State of Ohio, 5 have invented certain new and useful Improvements in Iron Wheels, of which the following is a specification.

The object of my invention is a light, durable iron wheel especially intended for wheelbarrows.

It consists in a peculiar construction of hub and spokes, by which the parts are cheaply produced and rapidly put together.

In the accompanying drawings, wherein like parts are indicated by similar reference-letters wherever they occur in the different views, Figure 1 is a side elevation of a wheel (partly broken away) embodying my improvements. The side clamping-plate is removed 15 and the coupling-sleeve shown in section. Fig. 2 is a diametrical section, showing the spokes in elevation and the inner end of one spoke removed to expose the seat wherein it is clamped. Fig. 3 is an elevation of one of 20 the spokes. Fig. 4 is an enlarged side elevation of the central notched disk, which receives the spokes. One of the spokes is shown in place in one of its notches. Fig. 5 is a side elevation of the central part of the 25 wheel drawn to the same scale as Fig. 4.

The hub of the wheel consists of a central disk, A, notched radially to receive the spokes B, and two face-plates, C, between which the disk A and spokes B are firmly clasped by the 30 screw-threaded sleeve D. The plates C are made of cast metal, and have around their inner faces half-round or V-shaped rings or beads e, which, when the two plates are clamped upon each side of the disk A, bear 35 upon beveled side of notches on the inner ends of the spokes B and force them outward against the tire E, thus rigidly securing the parts together. The plates C are bored out from the inside, and tapped to receive the 40 screw-threaded ends of the tube D, which is preferably a short piece of wrought-metal tubing. The tube is first firmly screwed into one of the plates C. The outer ends of both 45 plates are angular to provide a seat for the wrench, by which the plates are clamped upon the spokes B and disk A. The bore in

the outer ends of the plates C is smaller than the bore of tube D, and the tube does not reach the bottom of the perforations which receive it, so that the axle-bearings are at the 55 ends of the hub-plates. Friction is thus reduced, and a space left between the axle and tube to retain the lubricant. The spokes B, which are made, preferably, of flat bar-iron, have tenures at their outer ends to enter mortises in the tire E, and are notched at their 60 inner ends upon each edge at b, to receive the ring or flange e upon the plate C. The spokes being cut to the proper length and formed as shown, and the tire punched to receive the 65 tenons of the spokes, the spokes are inserted in place, the disk A placed in position with the inner ends of the spokes in its radial notches. The plate C, having the sleeve D secured in it, is then put in place by passing 70 the sleeve through the central opening in the disk A. The opposite plate is then screwed upon the end of the sleeve D until the disk and spokes are firmly clamped between the 75 two plates. The spokes in the meantime will be forced outward by the flanged ring e bearing upon their inclined shoulders, and the wheel is completed.

It is obvious that the sleeve D might be omitted, and the plates C clamped together by 80 bolts passing through their flanges and the disk A; but the construction I have shown is believed to be the best, as the wheel can be more readily put together and taken apart, and has a much neater appearance.

What I claim as new, and desire to secure by Letters Patent, is—

1. In an iron wheel, the combination of the mortised tire, the spokes tenoned at their outer ends and provided at their inner ends with 90 notches forming outwardly-inclined shoulders, the disk A, notched radially from its periphery to receive the inner notched ends of the spokes, side clamping-plates having annular flanges to bear against the inclined shoulders of the 95 spokes, and means for drawing said disks together to force the spokes outward against the tire, substantially as specified.

2. The combination, substantially as specified, of the central notched disk, A, the spokes B, having notched edges at their inner ends, 100 which ends fit into the notches in disk A, with

the plates C, having annular flanges c to bear against the inclined shoulders formed by the notches in spokes B, and the screw-threaded sleeve D, for drawing the said plates firmly upon the disk A and edges of the spokes.

5. In a wheel of the character described, the combination, substantially as specified, of the plates C, centrally bored and screw-tapped,

with the sleeve D, screw-threaded to engage the threads in the parts C, for the purpose of drawing the plates firmly upon the spokes.

LEVI H. GOODWIN.
